UNITED STATES PATENT OFFICE.

WILLIAM H. OSBORN, OF SEATTLE, WASHINGTON.

DOOR-HINGE.

1,284,135.

Specification of Letters Patent.

Patented Nov. 5, 1918.

Application filed November 1, 1917. Serial No. 199,780.

To all whom it may concern:

Be it known that I, WILLIAM H. OSBORN, citizen of the United States, residing at Seattle, in the county of King and State of Washington, have invented a certain new and useful Improvement in Door-Hinges, of which the following is a specification.

My invention relates to door hinges and the object of my invention is to provide door hinges the same pair of which shall be adapted to hinge a door to the door casing of either one of two different door frames in such manner that the inner side edge portion of said door shall engage with the adjacent door jamb when said door is closed, even though the door casing of said door frames be different in thickness, and each of which hinges shall embody a spring that is operatively adapted to exert its force to swing the door to a closed position, and the two members of each of which hinges shall be so pivotally joined that said members may be quickly separated to permit the removal of the door to which they are operatively attached.

I accomplish this object by devices illustrated in accompanying drawings, wherein—

Figure 1 is a view of the top end of a door hinge embodying my invention as it appears operatively associated with a door and the casing of a door frame;

Fig. 2 is a like view of the same door hinge in like association with the same door but with a different door frame whose casing is thinner than the casing of Fig. 1;

Fig. 3 is a view of the same hinge in vertical section on broken line 3, 3 of Fig. 1; and

Fig. 4 is a view of the same in side elevation.

Referring to the drawings, throughout which like reference numerals indicate like parts, 5 is one of the separable members of a door hinge which is articulated to the other member 6 thereof.

The member 5 is provided with integral lugs 7 and 8 disposed each to project at a right angle from a different one of the opposite end edges thereof both to extend edge-wise in an oblique right hand direction beyond the same side edge as shown in Figs. 1, 2 and 3.

Extending through both of the lugs 7 and 8, at directly opposite points thereof, are two spaced pivot bearing holes, one of the pivot bearing holes 9 being shown by a full

line and one of the pivot bearing holes 10 being indicated by a circular dotted line in Fig. 1, while in Fig. 2 the same one of the pivot bearing holes 9 is indicated by a circular dotted line and the same one of the pivot bearing holes 10 is shown by a circular full line.

The member 6 is disposed adjacent to and parallel with the member 5 and is provided with integral lugs 11 and 12 disposed each to project at a right angle from a different one of the opposite ends of said member 6 both to extend edgewise in an oblique left hand direction beyond the left hand edge thereof, whereby the outer side surfaces of the lugs 11 and 12 may be in contact with the inner surfaces of the lugs 7 and 8 as shown, the length of the member 6 being sufficiently shorter than the member 5 to permit said two lugs 11 and 12 to enter the space between said lugs 7 and 8.

The lugs 11 and 12 are shorter than the lugs 7 and 8 and each of said lugs 11 and 12 is provided with only one pivot bearing hole 13 whose axis is the same distance from the plane of the member 6 as the distance of the axial line of holes 9 is from the plane of the member 5.

A pivot rod 14 having a knob 15 is of dimensions to adapt it to be removably disposed, as in Fig. 1, to extend through the holes 10 of the lugs 7 and 8 and the holes 13 of the lugs 11 and 12, or to be removably disposed, as in Figs. 2 and 3, to extend through the holes 9 of the lugs 7 and 8 and said holes 13 of the lugs 11 and 12, whereby separable parts of the door hinge may be assembled to adapt it to hinge a door 16 to a thick casing 17 of a door frame 18 as shown in Fig. 1 or said parts may be differently assembled to adapt the hinge to hinge said door 16 to a thinner casing 19 of a door frame 20 as shown in Fig. 2.

If it be desired to remove the door 16 from a door frame without detaching the member 5 therefrom it is only necessary to remove the pivot rod 14 by grasping its knob 15 and pulling pivot rod 14 from the pivot bearing holes in which it is disposed thereby permitting the members 5 and 6 to be separated in an obvious manner.

In order that a door, when hinged by a hinge embodying my invention, as, for instance, a screen door that is commonly used to prevent house flies and mosquitos from entering a doorway, may be adapted auto-

matically to close, I have provided a helical spring 21 disposed within a tube 22 which is disposed to surround that portion of the pivot rod 14 that extends between the lugs 5 11 and 12, as indicated more clearly in Fig. 3.

Each end portion of the tube 22 is provided with a slot, as slots 23 and 24, through which may project outwardly end portions 10 25 and 26, respectively, of the spring 21, which end portions 25 and 26, are curved and engage with the members 6 and 5 respectively in such manner that they may easily slide thereon.

15 While I have shown the spring 21 and the tube 22 as associated with the two members of a hinge, such spring 21 and tube 22 may, if desired, under some conditions of use, be omitted.

20 Obviously changes may be made in the forms, dimensions and arrangement of parts of my invention without departing from the spirit thereof.

What I claim is:

25 1. In a metal hinge, the combination with two hinge sections, comprising co-acting leaves having pivoting lugs extending at right angles thereto in two different planes of engagement and fitting one within the other, the said lugs of one leaf being longer than those of the other leaf and each having

a plurality of bearing holes therethrough, of a pintle extending through the lugs of said other leaf and the desired bearing holes of the leaf having said longer lugs to pivot- 35 ally connect said hinge sections.

2. In a spring hinge, the combination with two metal hinge sections, comprising co-acting leaves having pivoting lugs extending at right angles thereto in two different 40 planes of engagement and fitting one within the other, the said lugs of one leaf being longer than those of the other leaf and each having a plurality of bearing holes therethrough, of a pintle extending through the 45 lugs of said other leaf and the desired bearing holes of the leaf having said longer lugs to pivotally connect said hinge sections, a tube surrounding said pintle and extending between said pivoting lugs, said tube having 50 transverse end slots, and a helical spring surrounding said pintle and positioned within said tube, said spring having its opposite ends extended through said slots of the tube and each bearing against one of said hinge 55 sections to maintain the spring under tension.

In witness whereof, I hereunto subscribe my name this 24th day of October, A. D. 1917.

WILLIAM H. OSBORN.
